 Bartlett, London, England, assignors to Siemens
 Brothers & Co. Limited, London, England, a
 British company

Application October 7, 1940, Serial No. 360,038
 In Great Britain October 10, 1939

11 Claims. (Cl. 179—16)

The present invention relates to telephone or like signaling systems and more particularly to feeding-bridge circuits in or for such systems.

With the types of feeding-bridge circuit commonly employed in practice, trouble is often caused by undesired current surges produced by signaling currents and especially by current surges produced during and as a result of impulse repetition. Such undesired current surges may be produced at the bridge itself or may be generated at some other point. They are likely to be especially troublesome in systems where they may reach a voice-frequency signal receiver of the kind liable to be temporarily paralysed by a strong input current.

The present invention has as one main object the provision of an improved feeding-bridge circuit wherein no surges of harmful magnitude can be set up or transmitted as the result of impulse repetition.

According to one feature of the invention a feeding bridge circuit is of the kind in which the incoming and outgoing lines are coupled solely by the transformer action of a repeating coil and an element or elements having non-linear resistance properties is or are connected to a winding or windings of the repeating coil in such a manner as to limit the magnitude of surges present at the bridge whilst having little effect on communication currents.

According to another feature of the invention a biassing voltage is applied to the non-linear resistance element, the poling of the element being such that in conjunction with the biassing voltage damping of communication currents is negligible. This biassing voltage may be obtained by a connection to a separate source of current or it may be provided by the drop in voltage occasioned by the flow of feed current through the repeating coil winding to which the non-linear resistance element is connected. The term "non-linear" resistance element is herein intended to include an element of which the resistance varies with the voltage applied to it and also to an element which offers a different resistance to the same voltage depending on the polarity of the voltage, i. e., it possesses unidirectional conductivity. An element of the first type is suitable for use in the case in which no biassing voltage is used and an element of the second type is employed in the case in which a biassing voltage is applied to the element. A dry-plate rectifier or an element of a known compound of silicon carbide in which the resistance offered is high when the voltage due to communication currents is applied but falls

to a lower value due to the application of a surge voltage higher than that produced by communication currents is suitable for use as a non-linear resistance element whether a biassing voltage is applied or not, it being understood that the poling of an element possessing unidirectional conductivity will be such that the element is suited to the connection in which it is employed and that any biassing voltage applied to the element will be such that the element does not become conductive to any great extent until the surge voltage exceeds that due to the communication currents.

In one way of carrying out the invention the 15 non-linear resistance elements may be connected across the windings of the repeating coil connected to the line and in the case of the windings on the incoming side of the bridge it is preferable to employ a balanced arrangement in 20 which an element is connected across each of two windings of the repeating coil on the incoming side of the bridge. It will be realised that such a device is half-wave in action and will deal effectively with surges arising at the bridge. It 25 will also deal effectively with surges arising at a preceding point provided that the current at that point which gives rise to the surge flows in such a direction that the initial polarity of the surge is the same as that which would be produced by 30 a surge at the bridge itself. In a telephone system this can usually be arranged to be the case.

In another way of carrying out the invention the non-linear resistance element or elements may be connected across a winding of the repeating coil other than a line winding and herein-after called a "third" winding irrespective of the 35 number of windings connected to the lines. The "third" winding may itself comprise two series connected windings. Two oppositely connected 40 elements may be connected to the "third" winding of the repeating coil to provide an arrangement full-wave in its action and independent of the polarity of the line wires.

In arranging for a bias on the elements when 45 connected across the line windings it may be found desirable to include an external resistance, which should be non-inductive, in series with a repeating coil winding and to connect the element across this series connection. The resistance 50 should be sufficiently low in value to prevent its presence from unduly affecting the efficiency of the bridge. The use of feed current to produce the bias where the non-linear resistance elements are connected to the line windings of the 55 repeating coil has the advantage that it is this

current which, when interrupted, gives rise to the surge and by its interruption the bias on the non-linear resistance element is removed rendering the arrangement more effective in dissipating the resultant surge.

In the case in which non-linear resistance elements are connected to the "third" winding of the repeating coil a suitable biassing voltage may be obtained either from a separate source of current or from suitable connections made to the source of feed current. However by the choice of a suitable element a biassing voltage may be dispensed with.

In an automatic telephone system the feeding bridge will include an impulse receiving relay on its incoming side. A relay having a low inductance and operating at a high speed such as the relay described in U.S. Patent No. 1,992,610, granted February 26, 1935, to E. J. Gachet, is suitable for use as an impulse receiving relay and a contact of this relay may be arranged to repeat the impulses in the outgoing side of the bridge or it may control an impulse repeating relay which may also be of the high speed type and a contact of this latter relay may be included in the outgoing line wires.

Specific embodiments of the invention will now be described by way of example with reference to the accompanying drawings. In the drawings Fig. 1 shows diagrammatically an outgoing repeater with a feeding bridge in which incoming impulses are repeated as D. C. impulses over an outgoing circuit, Figs. 2 and 3 show alternative forms of a similar repeater for repeating D. C. impulses as impulses of voice frequency current in an outgoing circuit, while Figs. 4, 5 and 6 show diagrammatically modifications of the arrangements at the feeding bridge that may be employed.

Reference will first be had to Fig. 1. The relay set here shown is for connection at the outgoing end of an inter-exchange junction which serves as a link between automatic switching equipments at the two telephone exchanges concerned, and as is usual in such relay sets it has incoming positive, negative, and private wires for connection to the multiple of a group of selectors in the same exchange as itself and outgoing positive and negative wires for connection to the two wires of the junction. In the drawings the incoming wires appear at the top on the left, the private wires being designated P. The outgoing wires appear at a corresponding position on the right, the private wire connection shown in this case being intended simply for extension to a distributing frame for use for the purposes of local testing. The contacts designated T are contacts of a test jack. It will be noted that underneath the reference character for each relay there is a digit indicating the number of contacts on that relay. For example, relay G is denoted by the letter "G" over the digit "3"; this means that relay G has three contacts, numbered g₁, g₂ and g₃.

The principal functions of the relay set are to supply loop current backwards towards the originating end of the connection, to control the loop circuit which extends forwards to the succeeding exchange, and to control the holding of the switches in the local exchange. In order that it may properly perform these functions it includes a transmission bridge and must hence be adapted to repeat received impulses and supervisory signals.

The relay set has a feeding bridge of the kind

in which the incoming and outgoing circuits are coupled together by a so-called repeating coil RC. This repeating coil has two windings I and III in the incoming circuit and two windings II and IV in the outgoing circuit. Windings I and III are connected in series via a 2-microfarad condenser QA and windings II and IV are connected in series via a 2-microfarad condenser QB. Connected in series with windings I and III respectively of the repeating coil RC and to the line are resistances R₁ and R₂ and across the series connection of winding I and resistance R₁ is connected a non-linear resistance element, suitably a dry plate metal rectifier, SR₁. A similar element SR₂ is connected across the series connection of winding III and resistance R₂. The connections on the incoming side of the feeding bridge are such that the incoming positive wire is normally connected to earth via winding I of a high-speed low-impedance impulse-receiving relay A and one element of a two-element ballast resistance BRA, and the incoming negative wire is normally connected to battery via winding II of relay A and the other element of BRA.

Condenser QB on the outgoing side of the bridge has two shunts connected across it. One of these shunts includes parallel connected rectifiers MRD polarised so as normally to allow current flow over the outgoing junction during the initiation and setting up of a connection; the other shunt includes rectifier MRC and relay D, rectifier MRC being so polarised as to allow relay D to operate only when current in the junction wires is reversed consequent on the reply of the called subscriber.

When the relay set is in circuit at an exchange and is free with its apparatus at normal, it tests free to a searching selector by reason of the absence of earth on the incoming private wire. When the relay set is seized for a call by such a selector, the high-speed impulse-receiving relay A is operated in a circuit which includes the impulsing loop which is controlling the setting up of the call. The actual operating circuit is from earth over the lower element of the ballast resistance BRA, winding I of relay A, winding III of the repeating coil RC resistance R₂, back contact dd₃, the incoming positive wire, the impulsing loop referred to the incoming negative wire, back contact dd₂, resistance R₁, winding I of the repeating coil, winding II of relay A, the upper element of the ballast resistance BRA to battery. With current flowing in this circuit the potential cross winding I of the repeating coil and resistance R₁ in series is applied to the non-linear resistance element SR₁ biassing it so that current through it at a voltage not higher than that due to speech in the circuit is effectively blocked. A similar biassing potential is applied to the element SR₂ by the drop in winding III of the repeating coil and resistance R₂. Relay A is preferably a relay of the kind illustrated and described in U. S. Patent No. 1,992,610, as before mentioned, and has only the one contact a₁, this being of the simple change-over type. Contact a₁ on operation closes operating circuits for a high-speed impulse-repeating relay AA and for the release relay B of the relay set, the circuit for relay AA comprising a rectifier MRB, winding I of the relay, and resistance YB. The said impulse-repeating relay is a relay of the same kind as relay A and its sole contact a₁ on operation closes a point in a calling loop across the outgoing positive and negative wires. A

spark-quenching combination comprising a condenser QC in series with a resistance is connected across the "make" portion of contact *a1*. It has been found that the presence of this combination exercises a beneficial effect on impulse repetition. The release relay B is as usual a relay which is slow to release. On its operation as just described, its contact *b1* connects earth derived via back contact *dd4* to the incoming private wire for engaging and holding purposes and contact *b2* connects a battery-connected switching relay HA to this wire and thereby brings about the operation of this switching relay. The circuit of relay HA includes a resistance YC, and the relay on operation locks up in a circuit over front contact *ha1* and at contacts *ha2* and *ha3* completes the calling loop over the outgoing line wires. Contact *b4* closes the operating circuit of a slow releasing relay G. Relay G operates and performs preparatory guarding operations. Consequent on the operation of relay HA, current flows over the outgoing junction and the parallel-connected rectifiers MRD but not through relay D owing to the polarity of rectifier MRC. The rectifier MRB is to prevent the winding of relay B from unduly increasing the release lag of relay AA by acting as a shunt. The connections of the repeating coil RC are such that during impulse repetition the currents in all four windings assist each other so far as the direct current magnetisation of the core is concerned.

Impulses are now received over the incoming line and are responded to by relay A. At the first interruption in the line current, relay A releases and at contact *a1* opens the circuit for relay AA. Relay AA releases and at contact *aa1* opens the outgoing loop to repeat the impulse break and closes a short-circuit across the outgoing side of the feeding bridge. Consequent on the closure of back contact *a1* a circuit is closed over contacts *dd5* and *b3* and the two windings of relay C in series and that relay operates. Contact *c1* short circuits winding I of the relay to render it slow in releasing and contact *c2* connects a low resistance shunt across the outgoing side of the bridge. Subsequent received impulses are repeated by relay AA over the junction.

In consequence of the opening of the incoming line wires the energy in the windings of the repeating coil tends to dissipate itself in the form of a surge. As regards the energy produced in the windings I and III of the repeating coil, a path for the surge current is provided over the elements SR1 and SR2 the bias on which was removed consequent on the cessation of current round the loop. The potential drop across winding I and resistance R1 and winding III and resistance R2 respectively is such as to cause a current to flow through the elements SR1 and SR2 and the voltage across the elements is reversed in polarity and the surge dissipates itself so that surge current of any magnitude is prevented from passing through the repeating coil to the outgoing line. By controlling the bias on the non-linear resistance elements by the feed current which on interruption gives rise to the surge, the bias is removed on interruption of the feed current and a rapid dissipation of the surge energy results. It will be noted also that the production of a surge of the same polarity at a preceding point will also be prevented from passing through the bridge without attenuation, the

elements SR1 and SR2 providing a suitable path for the dissipation of the surge energy.

At the end of each train of impulses relay C releases removing the shunt from the outgoing side of the bridge. After the connection has been completely set up and the called party replies, relay D is operated by current reversal over the junction. The closing of contact *d1* initiates the slow operation of an answering supervisory relay DD having a long operation lag, and contact *d2* completes a circuit for a holding winding II of the impulse-repeating relay AA. Relay DD on operation is temporarily locked up in a circuit over contacts *dd1* and *h4* and owing to its slow operating property serves to ensure that metering is not effected unless the reversed current condition in the outgoing line wires persists for a reasonable time. The changing over of contact *dd1* initiates the slow release of the metering relay G, and contacts *dd2* and *dd3* effect a reversal of current in the incoming line wires to repeat the answering supervisory signal in case this should be necessary. Contact *dd4* connects booster battery potential to the incoming private wire in place of the usual holding earth, so that if the calling party is a subscriber belonging to the exchange in which the relay set is situated, the meter of this party is operated in series with resistance YD. When the slow release of relay G is completed, contact *g1* opens the holding circuit of relay AA and contact *g2* closes an operating circuit for a control relay H which circuit includes contacts *b4*, *d1* and *h1*. On the operation of relay H, make-before-break contact *h1* renders the circuit of the relay independent of the condition of relays D and G, contacts *h2* and *h3* restore the usual holding condition on the incoming private wire, and contact *h4* opens a holding circuit for relay DD. Release of the switching relays connected to the private wire is prevented during the changeover period by the presence of holding earth applied over rectifier MRA which opposes flow of booster battery current. The condition of the circuit immediately subsequent to metering is that relays A, AA, B, HA, D, DD, and H are operated.

If at the end of the call the calling party clears first, then relay A releases, this release causing the immediate release of relay AA and initiating the slow release of the release relay B. The falling back of contact *aa1* opens the loop across the outgoing junction wires, releasing relay D and initiating the release of the apparatus at the distant end of the junction. The opening of contact *d1* releases relay DD. The falling back of contact *dd1* operates the metering relay G, and the falling back of contact *dd5* operates the dialling relay C. Contact *g3* closes an alternative circuit for relay C. Contact *c1* short-circuits the low-resistance winding I of relay C to render the relay slow to release. On the subsequent completion of the slow release of the release relay B, the opening of contact *b1* temporarily removes the holding earth from the incoming private wire to release the switching relay HA and the selector switching relays held locked to this earth (thus causing the immediate commencement of the release of the apparatus preceding the relay set), and the opening of contact *b4* releases relay H and initiates the slow release of relay G. The switching relay HA is arranged to release rather more slowly than the said selector switching relays, and when it does release, at contact *ha1* it completes a circuit over contact *c3* for again earthing the incoming private wire to

guard the relay set from seizure by a searching selector. On the completion of the slow release of relay G, the opening of contact g_3 initiates the slow release of relay C. On the completion in turn of the slow release of relay C, the guarding earth is disconnected from the incoming private wire and the relay set is ready for use on another call. Owing to the sequence of operations just described, the apparatus at the distant end of the junction is given ample time to release 10 before the relay set tests free, while the preceding apparatus is not held for the whole of the guarding period.

If the called party clears before the calling party, the polarised back-bridge relay D is in accordance with the hitherto usual practice released by the usual reversal of current in the line wires of the junction, and at its contact d_1 releases the answering supervisory relay DD. The falling back of contact dd_1 operates the metering relay G, and the falling back of contacts dd_2 and dd_3 effects a reversal of current in the incoming line wires to repeat the clearing signal in case this should be necessary. When the calling party clears, relays A and AA release in turn, relay C is operated over back contact a_1 , and the slow release of relay B is initiated. The falling back of contact aa_1 opens the loop across the outgoing junction wires, initiating the release of the apparatus at the distant end of the junction. On the subsequent completion of the slow release of the release relay E, release of the connection proceeds in the same manner as in the case considered in the preceding paragraph.

If the called party is not free when called, then busy tone current is received over the junction and passes via the repeating coil bridge to the calling party. When the calling party clears, relays A and AA release in turn, and release of the connection proceeds in a manner similar to that just described.

The feeding bridge shown in Fig 2 is suitable for use in a system in which incoming D. C. impulses are to be repeated as impulses of voice frequency current. The incoming side of the bridge is arranged in a manner similar to that shown in and described for Fig. 1. The repeating coil windings on the outgoingside of the bridge are connected to the outgoing junction over the back contact of a change-over spring set of a dialing relay and the front contact of a change-over spring set of an impulse repeating relay AA. The front contact of the change-over spring set of the dialing relay connects a 600 ohm termination across the line and the back contact of the change-over spring set of the impulse repeating relay connects the secondary winding of a tone transformer TT to the line. The primary winding of the tone transformer is connected to a source of voice frequency current. The impulse repeating relay corresponds to the relay designated AA in Fig. 1 and the dialing relay corresponds to the relay designated C in Fig. 1 and may be operated and controlled in well known manner. When the relay set is taken into use relay AA operates and at contact aa_1 disconnects the tone transformer from the line wires, it being understood that normally the line is held open by contacts of a switching relay which is operated to close the line circuit when the relay set is taken into use. On receipt of the first impulse break, relays A and AA release and by means of a previously prepared circuit the dialing relay is operated. Relay AA releases and connects the tone transformer to the line so that

for the duration of the break period a pulse of voice frequency current is transmitted. When the impulse repeating relay again operates, the 600 ohm termination is connected to the line over contact c_1 . The dialling relay remains operated throughout the duration of an impulse train and releases at the end of the train in known manner.

The action of the non-linear resistance elements SR1 and SR2 is the same as that described in connection with Fig. 1. With the arrangements described paralysation of the voice-frequency current receiver due to the transmission of surges can be reduced to a negligible amount. Like the case of Fig. 1 the surge limiting action is half-wave in its action and can deal with surges arising at the bridge and with surges arising at a preceding point if the polarity is the same. A surge limiting result may also be obtained by connecting a non-linear resistance element across the repeating coil windings on the outgoing side of the bridge. The element may be a rectifier and have a suitable biasing voltage applied to it. The magnitude of the biasing voltage and the poling of the element would be so arranged that a surge arising at the bridge would be shunted away from the line whilst communication currents would suffer little attenuation. Such an arrangement is illustrated diagrammatically in Fig. 3 in which the element is designated SR and the source of biasing voltage V. The remainder of the apparatus illustrated in this figure is similar to the correspondingly designated apparatus in Fig. 2. An advantage of this arrangement lies in the fact that it becomes effective before the dialling relay possessing contact c_1 operates and therefore is effective to deal with a surge arising from the transmission of the first impulse of a train.

As an alternative to the arrangement illustrated in Fig. 3 the element SR may be of a type which does not necessitate a biasing voltage, the resistance of the element under the communication current condition being sufficiently high to prevent appreciable damping of speech currents and under surge conditions sufficiently low for the rapid dissipation of the surge energy.

It has been found that with repeating coil windings of 10 ohms each and non-inductive resistances R1 and R2 also of 10 ohms each a suitable bias for a dry plate rectifier for use as SR1 and SR2 is obtained on a line up to 300 ohms loop resistance, the value of bias to be provided depending on the characteristics of the devices SR1 and SR2.

Other arrangements for providing the surge limitation coming within the invention are illustrated in Figs. 4, 5 and 6. In these figures, which are only diagrammatic, the repeating coil is shown with two line windings I and II and a third winding III to which non-linear resistance elements are connected. The arrangements shown in these figures are full-wave in action. In Fig. 4 two rectifiers SR1 and SR2 with like faces connected to the ends of the third winding of the repeating coil have their other faces connected together and to one end of a source of biasing voltage V the other end of the source being connected to the mid point of the third winding III. It will be seen that when the voltage induced in winding III exceeds the voltage of source V and opposes it the bias on the rectifiers is overcome and they become conductive and provide a low resistance shunt in which the surge may dissipate itself. The bias provided by the source V is such that

no appreciable shunting effect is present when communication currents are flowing in the repeating coil. It will be understood by those skilled in the art that each non-linear resistance element may be associated in opposite senses with a separate winding, the result being equivalent to the single winding with mid point connection shown in the figure. Furthermore, by the choice of a suitable element the element may be connected across the "third" winding of the repeating coil without the application of a biasing voltage.

The arrangements illustrated in Figs. 5 and 6 are similar in their action to those illustrated in Fig. 4 the source of biasing voltage being a potentiometer P connected across a battery V. These arrangements obviate the necessity for the use of a separate biasing battery and in a telephone system V may be the exchange battery.

It will be understood that a half-wave action may be had by the connection of only one rectifier to the winding III and the application of a suitable biasing voltage but the full-wave action deals not only with surges arising at the bridge but also with surges arising at a preceding point whether the polarity is the same or not.

We claim:

1. In combination, a circuit including resistance, means for impressing audio frequency upon said circuit, a source of direct current in said circuit biasing same to cause the flow of current over said resistance always to be in a particular direction even when said resistance is traversed by said audio frequency, a rectifier connected in shunt to said resistance, whereby the voltage drop in said resistance due to current flowing therethrough produces a difference of potential across said rectifier, said rectifier so poled with respect to said voltage drop that it will resist current flow through itself whenever the current flow through said resistance is in said particular direction, said rectifier becoming conductive whenever an abnormal potential in said circuit tends to reverse the current flow through said resistance, thereby to limit the magnitude of surges through said resistance.

2. In combination, a circuit including an inductance, means for impressing audio frequency upon said circuit, a source of direct current in said circuit biasing same to cause the flow of current through said inductance always to be in a particular direction even when said inductance is traversed by audio frequency, a rectifier connected across said inductance, whereby the voltage drop in said inductance due to current flowing therethrough produces a difference of potential across said rectifier, said rectifier so poled with respect to said voltage drop that it will resist current flow through itself whenever the current flow through said inductance is in said particular direction, said rectifier becoming conductive due to the surge from said inductance in the event the current flow from said source is interrupted.

3. In a telephone or like system, a communication line divided into two sections, a repeating coil inductively linking said two line sections, a source of direct current connected to one of said line sections over a circuit including a winding of said coil, said source effective to maintain current flowing through said circuit in a particular direction even when said winding of the repeating coil is traversed by speech currents, a rectifier connected in shunt to said circuit, whereby the voltage drop in said circuit due to

said current flowing therethrough produces a difference of potential across said rectifier, said rectifier so poled with respect to said voltage drop that it is substantially non-conductive so long as said current continues to flow in said particular direction through said circuit, said rectifier becoming conductive whenever an abnormal potential on said line tends to reverse the direction of current flow through said circuit, thereby to limit the magnitude of surges through said circuit.

4. In a telephone or like system, a battery feed bridge comprising a source of direct current, a relay having two windings, a repeating coil having a plurality of windings, two non-inductive resistors, a line having two conductors, means connecting one terminal of said source to one of said conductors over a circuit including one winding of said relay, one winding of said coil and one of said resistors in series, means connecting the other terminal of said source to the other of said conductors over a circuit including the other winding of said relay, another winding of said coil and the other of said resistors in series, a rectifier shunting that portion of said first circuit including said one winding of said coil and said one resistor, another rectifier shunting that portion of said second circuit including said other winding of said coil and said other resistor, each of said rectifiers being so poled that they offer high resistance to the flow of current from said source when said two conductors are connected together.

5. In a telephone or like system, a line divided into two sections, a repeating coil inductively linking said two line sections, a relay, a source of direct current, means connecting said source to one of said line sections over a circuit including said relay and a winding of said repeating coil in series, whereby a normal current flow is established over said relay, said winding and said one line section, said relay responsive to interruptions of said normal current flow, the inductance of said one line section and of said relay tending to cause current to surge through said winding in a direction opposite to said normal current flow upon each said interruption of said normal current flow, and a non-linear resistance connected in bridge to said winding and effective to limit the magnitude of said current surges through said winding.

6. In a system as claimed in claim 5, means controlled by said relay for repeating said interruptions as impulses over the other section of said line, and other means controlled by said relay upon commencement of said repetition for short-circuiting the winding of said repeating coil connected to said other line section.

7. In a telephone or like system wherein a connection may be extended from certain equipment to other equipment at will, wherein said other equipment thereupon is effective to impress a direct current potential upon two conductors of said extended connection, and wherein said other equipment thereafter is effective to reverse the polarity of the potential connected to said conductors for supervisory purposes, a first circuit bridging said two conductors in said certain equipment, said circuit containing a rectifier poled to permit current to flow over said circuit only when the potential impressed upon the conductors at said other equipment is of a certain polarity, a second circuit bridging said two conductors in said certain equipment, said second circuit containing a rectifier poled to permit cur-

rent to flow over said second circuit only when the potential impressed upon the conductors at said other equipment is of a different polarity, and a relay included in one of said circuits and operated whenever there is a current flow over that circuit due to the potential impressed upon the conductors at said other equipment.

8. In a telephone or like system, a communication line divided into two sections, a repeating coil having a different winding connected to each 10 of said line sections thereby to inductively couple said two sections, said repeating coil also having a winding other than those connected to said two line sections, a rectifier, a source of direct current, and means connecting said source, said rectifier and at least a portion of said other winding in a series circuit, said rectifier being so poled in said circuit that it presents high resistance to the flow of current over said circuit from said source.

9. A system such as claimed in claim 8, wherein the potential impressed upon said rectifier by said source is greater than that impressed thereupon due to the currents induced in said other winding when speech currents are present on 25 said communication line.

10. In a telephone or like system, a communication line divided into two sections, a repeating coil having a different winding connected to each 30 of said line sections thereby to inductively couple said two sections, said repeating coil also having

5 a winding other than those connected to said two line sections, a source of direct current having one terminal connected to the center point of said other winding, a rectifier connected between the other terminal of said source and one end of 15 said other winding, and a second rectifier connected between said other terminal and the other end of said other winding, each of said rectifiers being so poled that it presents high resistance to the flow of current over half of said other winding from said source.

11. In a telephone or like system, a communication line divided into two sections, a repeating coil having a different winding connected to each 20 of said line sections thereby to inductively couple said two sections, said repeating coil also having a winding other than those connected to said two line sections, a source of direct current, a voltage divider connected across said source, 25 means connecting the mid-point of said divider to one end of said other winding, a rectifier connected between the other end of said other winding and one terminal of said source, a second rectifier connected between said other end of said other winding and the other terminal of said source, each of said rectifiers so poled that it presents high resistance to the flow of current from said source over said other winding and one half of said divider.

DAVID LANGSFORD CLAY.

CHARLES JOHN CLIFFORD BARTLETT.
